WOOD-WAKEFIELD COMPANY, OF BOSTON, MASSACHUSETTS, A CORPORATION OF
MASSACHUSETTS.

APPARATUS FOR PRODUCING FABRIC OF NONFLACCID STRANDS.

Application filed November 22, 1924. Serial No. 751,519.

The present invention relates to apparatus for forming a pattern of non-flaccid strands and more particularly to this general type of apparatus designed for the production of 5 a pattern consisting of a series of longitudinal warp strands interlocked by spaced stakes.

One object of the present invention is to provide apparatus for rapidly and efficiently 10 producing a pattern consisting of longitudinal strands interlocked by transverse stakes which are inserted in a plurality of planes in a manner to materially increase the depth or 15 thickness of the pattern and materially improve the appearance of the fabric.

A further object of the invention is to re-organize and improve apparatus of this general character in order to increase the output and minimize stoppage through break- 20 age or injury of the strands during incorporation into the fabric.

A still further object of the invention is to provide a machine for the production of stake and strand fabric which facilitates 25 modification or varying of the pattern produced thereby.

With these and other objects in view, the various features of the invention consist in certain novel features of construction, combinations and arrangements of parts hereinafter described and claimed, the advantages of which will be obvious to those skilled in the art from the following description.

35 In the accompanying drawings illustrating the preferred form of the invention, Fig. 1 is a front elevation of a machine embodying the features of the invention; Fig. 2 is a left hand side elevation of the machine shown in Fig. 1; Fig. 3 is a detail sectional view taken upon the line 3—3 of Fig. 1 and illustrating a portion of the feeding and cutting mechanism for the stake; Fig. 4 is a detail side elevation illustrating another 40 view of the stake feeding mechanism; Fig. 5 is a sectional elevation upon the line 5—5 of Fig. 1 illustrating the guiding and shed forming mechanisms; Figs. 6 and 7 are details illustrating respectively a plan and elevation partly in section of one of the 45 shed forming bars; Figs. 8 and 9 are a plan and elevation respectively of the cooperating shed forming bars; and Fig. 10 is a detail 50 illustrating a section of the cooperating shed

forming bars in operative relation with longitudinal warp strands positioned in the shed and a cross stake in the shed passage thus formed.

According to the present invention, a pattern consisting of a series of longitudinal 55 strands is interwoven with a series of spaced transverse stakes. As indicated more particularly in Fig. 5, the stakes are inserted successively above and below straight longitudinal strands. Interposed between the 60 straight longitudinals and parallel thereto are strands which pass upon opposite sides of the upper and lower stakes, making the 65 extreme depth or thickness of the fabric equal to the diameter of two stakes and 70 three longitudinal strands. The production 75 of this pattern is accomplished by leading the longitudinal strands from a series of passages in a guide member to revolving shed forming members positioned in relatively close proximity to the guide member and designed to engage with the longitudinal strands and form shed passages which are positioned successively in different planes. The formation of successive sheds 80 in the longitudinal strands is accomplished by cooperating shed forming members revolving about parallel axes. Each shed forming member is provided with a plurality of sets of shed forming teeth disposed 85 at different distances from the axis. In the illustrated embodiment of the invention, a plurality of sets of shed forming teeth are 90 uniformly disposed upon radii of equal length and have interposed therebetween a 95 plurality of sets of shed forming teeth disposed upon radii of shorter length. The revolving shed forming members are so arranged with relation to one another that during the rotation of the members one set 95 of shed forming teeth disposed on the longer radius cooperates with a set of teeth disposed upon a shorter radius. With this construction, the shed passages are formed in 100 different planes.

The machine shown in the illustrated embodiment of the invention comprises a frame having side bars 20 and 22 with a drive shaft 24 journaled therein. Mounted on one end of the drive shaft is a drive 105 pulley 26, which drives the shed forming members and cross feed through a gear 28 and grooved pulley 30 respectively. The

shed forming members are indicated generally at 32 and 34 and consist of revolving carriers each provided with a plurality of sets of shed forming teeth disposed circumferentially. The cooperating shed forming members are mounted on parallel shafts 36 and 38 journaled above one another in the upper portion of the machine frame. The two shafts are caused to rotate in unison by intermeshing gears 40 and 42 mounted upon the extended ends thereof at the outside of the frame. The shafts are driven intermittently and in timed relation to the cross feed by a ratchet wheel 44 mounted on the shaft 36 and engaged intermittently by a pawl 46 pivoted at 48 upon a rocker arm 50 loosely journaled on the shaft 36, as indicated clearly in Figs. 1 and 2. The rocker arm is oscillated at the proper time intervals through a rotating cam 52 mounted upon a counter shaft 54 and connected to the arm through a lever 56 and an adjustable link 58. As shown more particularly in Fig. 2, the lever 56 oscillates about a fixed pivot 60 and is provided with a cam roll 62 at the end opposite the link connection 58. The cam roll is maintained in contact with the periphery of the cam 52 through a spring 64 connecting the hub of the lever with a fixed portion of the frame. Yielding engagement of the pawl with the teeth of the ratchet is provided by the spring 66 interposed between a projection on the arm 50 and a tail 68 formed on the pawl above the pivot. The counter shaft 54 is journaled in the side bars of the frame above the main shaft 24 and is continuously rotated from the main shaft through a large gear 70, which meshes with the drive pinion 28. With this construction, it will be evident that the shed forming members are revolved intermittently and in unison during the continuous rotation of the cam 52.

The longitudinal strands are conveniently guided to the revolving shed formers through the provision of a stationary guide bar 72 mounted on a cross beam 74 and having a series of guide passages 76 formed therein, which receive the longitudinal strands, as indicated more particularly in Fig. 5. It is desirable that the longitudinal strands be spaced in contact with one another and in order to secure this relatively close spacing successive strand passages in the guide member are disposed above and below one another, as indicated in Figs. 1 and 5. The rotation of the shed formers draws the longitudinal strands through the stationary guide member and disposes these strands on the opposite sides of a transverse shed passage. Thereafter the rotation of the shed forming members is stopped for a sufficient time interval to permit the insertion of a cross stake in the passage thus formed. The cross stake is inserted through

an opening 80 formed in the frame opposite one end of the shed forming members and having cooperating feed rolls 82 and 84 positioned opposite the entrance thereof. The upper feed roll 82 is provided with a grooved periphery approximating the diameter of the cross stake and is continuously rotated from a pulley 86 mounted upon the opposite end of a short shaft 88. This pulley is driven by a flexible belt 90 passing through the side bar of the frame and thence diagonally to a drive pulley 92. During its passage between the drive pulley 92 and the smaller pulley 86, the belt is caused to pass over guide pulleys 94 and 96, as indicated in Fig. 3. Mounted upon the shaft with the guide pulley 92 is a smaller pulley 98 which is driven from a pulley 100 through a flexible belt 102. The main drive pulley 100 is mounted upon the shaft 24 and is rotated therewith. It will be evident that with this construction the stake feeding member 82 is rotated at a relatively high rate of speed. Cooperating with the grooved feed roll 82 is an underfeed 84 which is adapted to enter the groove in the upper roll and engage the strand therein. The lower feed member is loosely journaled upon the end of a lever 104 pivoted upon the frame at 106 and adapted to be oscillated at predetermined intervals by a path cam 108. The path cam is connected to the lever 104 through a rocker arm 110 and a link connection 112. As indicated, the rocker arm is normally maintained in contact with the periphery of the cam by a tension spring 114. The underfeed roll 84 is caused to maintain a yielding engagement with the strand by virtue of a pin and slot connection 116 between the end of the lever 104 and the link 112 and a light spring 118 connecting the lever with the link. With this construction, when the rocker arm 110 reaches a predetermined point on the periphery of the cam 108 the underfeed roll 84 is elevated into the grooved periphery of the continuously rotating feed member 52 to cause a stake previously positioned therein to be rapidly fed through the shed passage. Upon the complete insertion of the stake within the shed passage, the underfeed roll 84 is disengaged and the feeding movement ceases. If so desired, the feeding movement may be positively limited by a fixed stop (not shown) positioned at the opposite end of the shed passage.

At the completion of the feeding movement, the stake is automatically severed inside of the frame. This severing of the stake is accomplished by an oscillating knife blade 120 pivoted on the inside of the frame at 121 and operated at predetermined intervals by a rotary cam 122 connected to the knife blade through a rocker arm 124 and link 126. As indicated, the knife blade is

provided with a cutting edge 128 which shears the strand against the edges of an opening formed in a cutting plate 130, all as indicated in Fig. 3. Both the feed cam 5 and cutting cam are mounted upon the counter shaft 54. The rocker arms 110 and 124 are loosely journaled upon a counter shaft 60, which also carries a rocker member 56 at its opposite end.

10 The revolving shed forming members which are shown in assembled relation in Fig. 1 partially broken away to indicate the strand guide are illustrated more particularly in Figs. 5 to 10 inclusive. Each of 15 these shed forming members comprises essentially a hub portion 140 having a plurality of bars 144 disposed about the circumference. Interposed between the bars 144 is a second series of bars 146 also disposed circumferentially of the hub. Each of these 20 bars, as indicated more particularly in Figs. 6 to 9, is provided with a series of shed forming teeth denoted respectively by 148 and 150. The shed forming teeth 150 formed upon the bars 144 are deeper than the teeth formed upon the bars 146. On the other hand, the teeth formed on the bars 146 are disposed at a greater distance from the axis of rotation than the adjacent teeth 25 on the bars 144. Each bar is provided with a longitudinal slot 150 and 154 respectively which forms the shed passage in conjunction 30 with the cooperating shed forming member.

As indicated clearly in Fig. 5, the two revolving shed forming members are so located with respect to one another that the shed forming teeth upon the bar 146 mesh with the teeth on the bar 144 mounted upon the cooperating hub member. With this 40 construction, shed passages are formed successively above and below a given plane, which in the present instance may be considered the plane of the straight longitudinal strands. At the same time longitudinal strands upon opposite sides of the straight strands are engaged by the teeth on the cooperating shed forming members and deflected alternately above and below the shed 45 passage. It will be evident from Figs. 5 and 10 that the bottom portions of the shed forming teeth are positioned slightly beyond the bottom of the transverse shed slot passing therethrough so that the cooperating high and low teeth deflect the longitudinal 50 strands into positions where they project only slightly, if at all, into the transverse shed passage. The spacing between the bottom of one set of teeth and the tops of the cooperating teeth is sufficient to permit insertion 55 of a longitudinal strand without injury but engages the strand sufficiently to feed the finished pattern longitudinally as the shed forming members are revolved. It 60 will be evident from this construction that by replacing any given set of shed forming

bars with bars of a different character the character of the pattern may be varied. As the bars do not extend completely across the width of the machine, it will be evident that the pattern may be varied throughout its 70 width by employing shed forming bars having teeth of a different character or width. As indicated, the shed forming bars are secured to the hub through threaded fastenings 156.

As the meeting plane of the revolving shed forming members is varied between the formation of successive shed passages, it is important that means be provided for accurately guiding the cross stake into the 80 shed passage thus formed. To this end, cooperating guide disks 160 and 162 are mounted upon the shafts adjacent the ends of the shed forming members. Each of the guide disks is provided with a set of inclined guiding grooves 164 and 166, which, as indicated more particularly in Fig. 1, cooperate to provide a strand guiding groove. These strand guiding grooves are successively inclined in opposite directions 85 to provide a series of guide openings having entrance points positioned in the same plane and exit points positioned successively above and below such a plane. With this construction, the cross stake inserted through 90 the cooperating feed rolls is properly guided into the end of the shed passage.

While it is preferred to employ the specific construction and arrangement of parts shown and described, it will be understood that this construction and arrangement is not essential except so far as specified in the claims and may be changed or modified without departing from the broader features of the invention.

The invention having been described, what is claimed is:

1. Apparatus for producing a fabric of non-flaccid strands comprising cooperating shed forming members, means for revolving the members in timed relation, a plurality of sets of shed forming teeth disposed circumferentially about each of the members, successive sets of teeth on the two members cooperating to form shed passages in different vertical positions, means for guiding a series of parallel strands to the shed formers, and means for guiding cross strands to the shed passages thus formed.

2. Apparatus for producing a fabric of non-flaccid strands comprising cooperating shed forming members, a plurality of sets of shed forming teeth disposed circumferentially about each member at different distances from the axis of rotation, means for intermittently revolving the members in timed relation, means for guiding parallel strands to the members, and means for guiding a cross strand into the shed passage thus formed.

3. Apparatus for producing a fabric of non-flaccid strands comprising a stationary guide member having a series of parallel guide passages, revolving shed formers positioned in proximity thereto, a series of cooperating shed forming teeth mounted upon the members and designed to deflect predetermined parallel strands and to maintain predetermined strands against deflection to form a shed passage therethrough, means for intermittently revolving the members, and means for guiding cross strands to the shed passages thus formed.
4. Apparatus for producing a fabric of non-flaccid strands comprising two revolving members, a plurality of sets of shed forming teeth disposed circumferentially about each of the members, successive sets of teeth being disposed upon radii of different lengths, means for intermittently revolving the members, means for guiding a series of parallel strands between the members, and means for guiding cross strands to the shed passages formed by the members.
5. Apparatus for producing a fabric of non-flaccid strands comprising revolving shed forming members having a plurality of sets of cooperating shed forming teeth, the meeting planes of successive sets of teeth being spaced radially, means for intermittently revolving the members, means for guiding a series of parallel strands between the members, and means for guiding cross strands to the shed passages thus formed.
6. Apparatus for producing a fabric of non-flaccid strands comprising means for guiding a series of parallel strands, cooperating shed forming members having a plurality of shed forming teeth designed to successively deflect predetermined strands above and below a given median plane and to maintain other predetermined parallel strands against deflection to form successive shed passages at opposite sides of the median plane, and means for inserting cross strands in the shed passages thus formed.
7. Apparatus for producing a fabric of non-flaccid strands comprising a stationary guide member for guiding a series of parallel strands, revolving shed forming members positioned in proximity thereto, each having a plurality of shed forming teeth designed to deflect predetermined parallel strands and form shed passages therebetween, guide members revolving with the shed formers, each having a series of guide grooves cooperating to form oppositely inclined guide passages, and means for periodically feeding cross strands into the guide passages so formed.

In testimony whereof I have signed my name to this specification.

FRANCIS B. RILEY.
